UNITED STATES PATENT OFFICE.

ADOLPH POTDEVIN, OF BROOKLYN, NEW YORK, ASSIGNOR TO POTDEVIN MACHINE COMPANY, OF BROOKLYN, NEW YORK, A CORPORATION OF NEW YORK.

PAPER-BAG MACHINE.

1,176,164.

Specification of Letters Patent. Patented Mar. 21, 1916.

Original application filed November 12, 1912, Serial No. 730,973. Divided and this application filed January 21, 1915. Serial No. 3,451.

To all whom it may concern:

Be it known that I, ADOLPH POTDEVIN, a citizen of the United States, and resident of Brooklyn, in the county of Kings and 5 State of New York, have invented certain new and useful Improvements in Paper-Bag Machines, of which the following is a specification.

In accordance with an official requirement 10 the invention forming the subject of the present case is divided out of my pending application, Serial No. 730,973, filed November 12, 1912, for certain improvements in and relating to machines for making paper 15 bags.

The present invention concerns mechanism for severing successive blanks from paper tubing, and it has reference more particularly to means for severing bag blanks from 20 tubing preparatory to delivery to bottoming instrumentalities.

The invention also comprises, in combination with the severing mechanism, a novel construction and relative arrangement of 25 gripping, drawing and forwarding rollers whereby, with slight adjustment of parts, blanks of various lengths may be uniformly delivered to the bottoming mechanism.

The invention also embodies novel structural features, all of which will be herein-after fully described and definitely claimed. 30

In the drawings—Figure 1 is a plan of a portion of a bag making machine embodying the preferred form of my invention. 35 Fig. 2 is a longitudinal vertical section, as on the line 2—2 of Fig. 1. Fig. 3 is a similar section, enlarged, of the tube cutting mechanism and adjuncts. Fig. 4 is a partial elevation of the machine, showing driving gearing for the tube-cutting and other mechanisms.

1 designates the main supporting frame, and 2 the main driving shaft journaled in suitably located bearings in the sides of the 45 frame. At one end of the frame is mounted a roll of paper from which the bags are to be made, which paper is impelled to suitable pasting and forming devices by means of which it is progressively converted into an 50 appropriate tube in the usual manner.

At the delivery end of the tube-forming mechanism projects the usual forming plate 3 which is substantially equal in width to the internal width of the tube and which

plate is incased by the tube during its travel. 55 The free edge of this plate extends at a right angle to the path of travel of the tube, or substantially so, and is preferably serrated as at 4. Immediately above the plate and slightly in rear of its serrated 60 edge is a bar 5, the forward edge of which is also preferably serrated, as at 6. Hence if the leading end of the tube be advanced beyond the serrated edges and be securely held, and the portion of the tube contiguous 65 to such edges then be forcibly raised against the latter, the upper and lower sides of the tube will be transversely severed along the lines of the serrated edges, with one side of the tube extending slightly be- 70 yond the other.

The progressive feeding of the leading end of the tube to and beyond the serrated cutting members is effected by a pair of rollers 7 which constitute part of the usual 75 tube forming mechanism; which rollers are concertedly driven by appropriate gearing, including the meshing gear wheels 7* (Fig. 4), on their respective shafts.

Forwardly of the cutting members is a 80 pair of parallel shafts 8 provided with intermittently-acting pinch rollers 9 between which the leading end of the traveling tube extends, said rollers being provided with peripheral ribs 10 which are so disposed as 85 to bite and clamp the tube at predetermined intervals during its travel and thus temporarily hold the tube. The ends of the roller shafts 8 are provided with meshing gear wheels 11, (the upper one of which appears 90 in Fig. 1) the lower shaft being provided with a gear wheel 12 which is driven from a gear wheel 13 on the driving shaft through an intermeshing idler gear 14. Thus the pinch rollers are continuously driven. The 95 timing and relation of the parts are such that the clamping of the tube by the pinch rollers is effected when the tube is in proper position for severance at the serrated members. At this juncture an upwardly-traveling bar 15 is brought forcibly against the under side of the tube, immediately in front of said members, thereby sharply severing the blank from the body of the tube. This bar is carried by a pair of spaced endless 105 chains 16 which pass around upper and lower sprocket wheels 17, 18 respectively. In the preferred form of my invention the

upper wheels are loosely mounted on the shaft 8 and the lower wheels are fixed to a shaft 19 which has its bearings in the sides of the main frame. The latter shaft is provided at one end with a gear wheel 20 which meshes with and is driven by the idler gear wheel 14 above mentioned, the coöperative relation of the parts to each other being such that in each cycle of travel of the chains the bar 15 forcibly impinges against the underside of the clamped tube and effects the severance of a blank therefrom. As above described it will be seen that the active stretches of the chains pass between the 15 pinch rollers and the cutting members, and that as these clamping and severing mechanisms comprise continuously rotating parts they can be effectively driven at a relatively high speed.

20 When the tubing has been advanced into position to be clamped by the rollers 9, its free end extends between a pair of drawing rollers 22, 23, one (22) of which is mounted on the main shaft and the other (23) on an 25 upper parallel shaft 24. The periphery of the upper roller is mutilated as at 25 in order that the blank shall be intermittently grasped and released by the segmental acting surface 25' of the roller, such surface being arranged to grasp the blank immediately after it has been severed from the body of the tube and released by the pinch rollers 9, and being of sufficient circumferential extent to advance the blank to the bite of a 30 pair of forwarding rollers 26, 27 which are carried by parallel shafts 28, 29, respectively, having their bearings in boxes in the sides of the main frame. The roller 23 is secured to its shaft 24 by means of a set-screw 28a in the hub of the roller, whereby 35 said roller may be nicely adjusted about the shaft in order to set its acting surface at any predetermined position in relation to the roller 22, as the length of the blank may 40 require.

The shafts of the forwarding rollers 26, 27 are provided at one side of the machine with meshing gear wheels 33, and the lower shaft is provided at the other side of the machine with a gear wheel 34 in mesh with an idler 35 which, in turn, meshes with the gear wheel 13 on the drive shaft. Thus the rollers 26, 27 are properly driven in order to advance the blank toward the gripper cylinder 36.

As is understood the speed at which the tubing is fed to and across the path of the cutting and gripping mechanisms determines the length of the blanks, such speed 45 being prescribed by the gearing of the feed rollers 7; and as the cylinder and forwarding rollers are driven at a fixed speed relatively to each other it has heretofore been necessary to adjust them bodily toward and from the feed rollers 7 in order to adapt said

forwarding roller and its correlated bottoming mechanism to receive blanks of different lengths. By the employment, however, of drawing rollers of the character above described, I am enabled simply by the rotary 70 adjustment of the roller 23 to vary its point and period of engagement with the roller 22 to accord with the predetermined length of the blanks and thus accomplish their uniform feeding and delivery to the forwarding 75 roller and gripper cylinder.

Without limiting myself to the specific details of construction shown and described, what I claim is:—

1. The combination with a stationary cutting member, of means in advance thereof for grasping and temporarily holding the leading portion of a tube, a bar adapted to travel in a path adjacent to and at right angles, or substantially so, to the cutting member and between said cutting member and the holding means, continuously moving means carrying said bar, and means for supporting and impelling the last-named means. 80

2. The combination with a stationary cutting member, of means in advance thereof for grasping and temporarily holding the leading portion of a tube, a bar adapted to travel in a path adjacent to and at right angles, or substantially so, to the cutting member, endless carriers for said bar, and means for supporting and impelling said carriers. 85

3. The combination with a stationary cutting member, of a pair of rollers in advance thereof provided with co-acting pinch ribs, means for continuously rotating said rollers, a bar mounted to travel between said rollers and the cutting member in a plane at right 90 angles, or substantially so, to the latter, endless carriers for said bar, and means for supporting and impelling said carriers. 100

4. The combination with a stationary cutting member, of endless carriers, a bar connecting the same, means for supporting and impelling said carriers, whereby the said bar is caused to travel in a vertical plane adjacent the cutting member, and means located between the forward and rearward stretches 105 of the carriers for grasping and temporarily holding the leading portion of a tube. 110

5. The combination with tube-cutting devices, and means for feeding material to and across the path thereof, of means succeeding said devices for grasping and temporarily holding the leading portion of the material preparatory to the severance of a blank therefrom, and intermittently-acting blank-drawing rollers succeeding the holding devices, said rollers being so spaced and timed in relation to the said cutting and holding devices that the free end of the material extends between the rollers while it is engaged by the holding devices, and that the blank 120 125 130

is grasped by the rollers after it has been severed from the body of the material and released by the said holding devices.

6. The combination with tube-cutting devices, of means in advance thereof for grasping and temporarily holding the leading portion of a tube, a pair of intermittently-acting blank-drawing rollers in advance of said holding means, one of said rollers having a segmental acting surface, and means for adjusting the latter roller in respect to the other in order to vary the time and period of operation of said surface.

7. The combination with tube-cutting devices, and means for feeding material to and across the path thereof, of means succeeding said devices for grasping and temporarily holding the leading portion of the material preparatory to the severance of a blank therefrom, and intermittently-acting blank-drawing rollers succeeding the holding devices, said rollers being so spaced and timed in relation to the said cutting and holding devices that the free end of the material extends between the rollers while it is urged by the holding devices, and that

the blank is grasped by the rollers after it has been severed from the body of the material and released by the said holding devices, together with forwarding devices to which the blank is delivered.

8. The combination with tube-cutting devices, of means in advance thereof for grasping and temporarily holding the leading portion of a tube, a pair of intermittently-acting blank-drawing rollers in advance of said holding means, one of said rollers having a segmental acting surface, means for adjusting the latter roller in respect to the other in order to vary the time and period of operation of said surface, a pair of forwarding rollers in advance of said drawing rollers, and a gripper cylinder to which the blank is delivered by the forwarding rollers.

Signed at Brooklyn, in the county of Kings and State of New York, this 13th day of January A. D. 1915.

ADOLPH POTDEVIN.
